UNITED STATES PATENT OFFICE.

LOUIS J. STREUN, OF NEWARK, NEW JERSEY, ASSIGNOR TO BEAVER MACHINE & TOOL COMPANY, OF NEWARK, NEW JERSEY, A CORPORATION OF NEW JERSEY.

DESIGN FOR A PENDANT SWITCH.

58,838.

Specification for Design.

Patented Aug. 30, 1921.

Application filed March 21, 1921. Serial No. 454,294. Term of patent 7 years.

To all whom it may concern:

Be it known that I, LOUIS J. STREUN, a citizen of the United States, residing at Newark, in the county of Essex and State of New Jersey, have invented a new, original, and ornamental Design for a Pendant Switch, of which the following is a specification, reference being had to the accompanying drawing, forming part thereof, in which—

Figure 1 is an elevation, and Fig. 2 a plan of a pendant switch showing my new design.

I claim:

The ornamental design for a pendant switch, as shown.

LOUIS J. STREUN.
